United States Patent Office

Des. 183,463
Patented Sept. 2, 1958

183,463

COMBINED AQUARIUM AND BASE THEREFOR

James L. Mallamace, San Jose, Calif.

Application February 18, 1957, Serial No. 44,897

Term of patent 14 years

(Cl. D91—2)

FIG-1

FIG-2

FIG-3

FIG-4

Fig. 1 is a top plan view showing my new design for a combined aquarium and base therefor.

Fig. 2 is an enlarged side elevational view of Fig. 1;

Fig. 3 is a front elevational view thereof; and

Fig. 4 is a rear elevational view thereof.

I claim:

The ornamental design for a combined aquarium and base therefor, as shown.
